J. L. MUELLER.
MEASURING AND CUTTING MECHANISM.
APPLICATION FILED JULY 23, 1917.

1,353,661.

Patented Sept. 21, 1920.

Inventor: JOHN L. MUELLER,
By John W. Brumley,
His Attorney.

UNITED STATES PATENT OFFICE.

JOHN L. MUELLER, OF ST. LOUIS, MISSOURI.

MEASURING AND CUTTING MECHANISM.

1,353,661.

Specification of Letters Patent. Patented Sept. 21, 1920.

Application filed July 23, 1917. Serial No. 182,337.

To all whom it may concern:

Be it known that I, JOHN L. MUELLER, a citizen of the United States, and residing at St. Louis, Missouri, have invented the new and useful Improvement in Measuring and Cutting Mechanisms, of which the following is a specification.

This invention relates to measuring and cutting mechanism, and more particularly to measuring and cutting mechanism for table oil cloth. This application is a continuation in part of application Serial Number 833,934, filed April 23, 1914.

Table oil cloth is supplied in rolls and is often sixty inches wide; the rolls are, therefore, as much as sixty inches in length. Such oil cloth is comparatively thin and has no stiffness, so that it is rather inconvenient to handle. Such oil cloth has, moreover, a pattern on one side, and this pattern is on the inside when rolled up; but when displayed, the pattern should be on the outside.

One of the objects of this invention, therefore, is to provide mechanism for accurately dispensing, measuring and cutting oil cloth, constructed so that the oil cloth can be measured directly from the rolls, and accurately measured and cut square across.

Another object is to provide mechanism for rewinding the oil cloth, so as to place the pattern on the outside.

Further objects will appear from the detail description taken in connection with the accompanying drawing, in which,

Figure 1 is a side elevation of a combination display and dispensing device embodying this invention;

Fig. 2 is an enlarged detail taken in the direction of the line 2—2, Fig. 1;

Fig. 3 is a section on the line 3—3, Fig. 1;

Fig. 4 is a detail of Fig. 3, showing the measuring device;

Fig. 5 is a detail of one end of the carrier, showing the latching device;

Fig. 6 is an enlarged section on the line 6—6, Figs. 1 and 2; and,

Fig. 7 is a detail perspective of the winding roll.

Referring to the accompanying drawing, 10 designates a base supporting a rotary carrier 11, which rotary carrier is adapted to detachably support rolls of oil cloth 12, at the top and bottom. Clamps 13 are provided for clamping the rolls intermediate their ends, and hold the oil cloth in rolled

up condition. The carrier is also provided with a removable top 14, for covering the ends of the rolls. This display stand is fully shown and described in my patent 60 Number 1,144,229, patented June 22, 1915.

The base 10 has secured thereto, a laterally extending bracket 15, provided with a foot 16 for supporting a standard 17. This standard has mounted thereon, a bracket 65 19, which forms a bearing for a shaft 20 of the dispensing carrier, as hereinafter described.

The dispensing carrier comprises a pair of end plates 35 connected by cross bars 36 70 and 37, in any suitable manner. The cross bar 36 has secured thereto, the shaft 20, heretofore described as pivoted in the bearing bracket 19. Connecting the bars 36 and 37, is a formed sheet metal plate 40, which 75 forms a pocket for receiving the roll 12 of oil cloth. A roll 42 is provided with pintles one 44 entering a hole in one plate 35, and the other 45 being engaged by and locked in position by a latch 47, pivoted on the 80 other plate 35. This roll is provided with a crank 48.

Pivoted on the cross bar 36 is an arm 55, which supports the measuring mechanism, this mechanism comprising a case 60, carrying a dial 63, graduated in yards or any other suitable denomination, and carrying also a wheel 66, engaging the upper surface of the pipe or guide 37. This wheel has a shaft geared to the shaft of the pointer 68, 90 by a worm and wheel connection, so that rotation of the wheel 66, will rotate the pointer 68. The shaft of this pointer is frictionally connected with the worm wheel, and a knurled head 67 is provided which 95 is fixed to this pointer shaft, so as to permit setting of the pointer by the hand. The arm 55 is provided with a tail piece 54, so that when this arm is swung back, this tail piece will engage the cross bar 36, and limit 100 the movement of the arm and the measuring devices attached thereto.

The cross bar 36 is provided with an arm 22, the extremity of which moves over a quadrant 23, attached to the standard 17. 105 This arm carries a boss 24, which is formed hollow and is provided with a plunger 25, engaged by a spring 26, and adapted to engage recesses 27 and 28, in either the quadrant 23 or the standard 17. This plunger is 110 provided with a knurled head 29, so that it may be drawn out of the coöoperating recess.

With this construction, the carrier may be positioned on the standard in either vertical or horizontal position, and is latched in each of these positions.

- 5 The plates 35 are provided with centering devices, which are adapted to center the rolls and hold these rolls in position. For this purpose, one of these plates is provided with a sleeve 30, carrying a pin 31, adapted to 10 enter the roll, this pin being slidable in the sleeve and retained in a position of adjustment by a set screw 32. The other plate is provided with a similar pin or plunger 33, having a knurled head, but this pin or plunger is constructed as shown in Fig. 6, so 15 that it may be moved axially, by gripping the knurled head 34.

The upper face of the hollow cross bar 37 is provided with a slot 75, extending there- 20 along, and opposite the point of contact of the roll 66 therewith, for a purpose herein- after to be described.

A roll 70 is provided with suitable pintles 71 and 72, adapted to engage the bear- 25 ings in the end plates 35, one of the pintles 72 being provided with a handle 73. The purpose of this roll is to permit rewinding of the oil cloth.

The dispensing carrier is arranged to be 30 swung from a vertical to a horizontal position on the standard 17, and latched in either position by the latching device 25. When oil cloth is to be dispensed, the carrier is swung to a horizontal position, and it 35 will, at that time, be of convenient height. The oil cloth as received is, as referred to above, arranged with the pattern in. To re- wind this oil cloth, the roll is placed in the carrier, as shown in Fig. 3, while the roll 70 40 is placed in the slots 46, and the oil cloth is wound on the roll 70. At this time, the measuring device may also be swung over into operative position, as shown in Fig. 3, so as to check up the amount of oil cloth in 45 the roll. The roll of oil cloth is now re- moved, and the roll 70 removed from the rolled up material.

When it is desired to dispense oil cloth, a roll is placed in position, as shown in Fig. 50 3, between the centers 31 and 33, and the carrier 55 is swung into operative position, so that the wheels 66 will bear on the cross bar 37. The oil cloth is now partially un- 55 rolled by hand, and in doing so, rotates the wheel 66, and passed once around the winding roll 42, (which has been replaced). The handle 48 is now turned until the desired amount of oil cloth, so indicated by the position of the pointer on the dial, has been 60 drawn from the roll. As soon as this has been accomplished, the carrier 55 is swung in the direction of the arrow, and a knife is passed along the support 37, the knife en- 65 gaging the slots 75, so as to conveniently cut off the measured amount. The roll of oil

cloth is then returned to the stand, the measured part removed with the winding roll 42, from the carrier, and the measured part slipped off. The carrier can now be swung to vertical position and latched in position. 70

The measuring device is not only simple in construction, but is so constructed that there will be no slipping of the oil cloth with respect to the measuring wheel. The point of contact between the measuring 75 wheel and the oil cloth coincides exactly with the cutter slot 75 which is brought about by forming the pronounced bend so as to insure a line contact at the cutting point. It is, therefore, insured that the oil cloth will 80 be cut at the exact point as measured from the end of the piece.

It is obvious that various changes may be made in the details without departing from the spirit of this invention. It is, therefore, to be understood that this invention is not to be limited to the specific construction shown and described. 85

Having thus described the invention, what is claimed is:

1. In a device of the class described, a dispensing carrier constructed to support a roll of goods and permit the goods to be unrolled therefrom, a support over which the goods are adapted to be drawn, constructed and positioned to form a pronounced bend in the goods, said support having a cutting slot extending therealong and at the bend formed in the goods, and a measuring device having a wheel engaging the 95 goods at a point coincident with said slot as the goods pass over said support.

2. In a device of the class described, a dispensing carrier constructed to support a roll of goods and permit the goods to be un- 105 rolled therefrom, a support, arranged above and extending along the roll while supported on said carrier, over which the goods are adapted to be drawn, constructed and positioned to form a pronounced bend in the 100 goods, said support having a cutting slot extending therealong and at the bend formed in the goods, and a measuring device having a wheel engaging the goods at a point coincident with said slot as the goods pass 110 over said support.

3. In a device of the class described, a dispensing carrier constructed to support a roll of goods and permit the goods to be un- 120 rolled therefrom, a support fixed in the carrier over which the goods are adapted to be drawn, constructed and positioned to form a pronounced bend in the goods, said support having a cutting slot extending therealong and at the bend formed in the 125 goods, a measuring device engaging the goods as it passes over said support, and means for supporting said carrier, constructed to permit it to move to vertical and horizontal positions. 130

4. In a device of the class described, a dispensing carrier constructed to support a roll of goods and permit the goods to be unrolled therefrom, a winding roll receiving the goods from the roll, a support fixed in the carrier between said rolls constructed and positioned to form a bend in the goods as they pass thereover, said support having a cutting slot extending therealong and at the bend formed in the goods, and a measuring device engaging the goods at a point coincident with said slot as the goods pass over said support.

5. In a device of the class described, a dispensing carrier constructed to support a roll of goods and permit the goods to be unrolled therefrom, a fixed support over which the goods pass, constructed and positioned to form a pronounced bend in the goods, said support having a cutting slot extending therealong and at the bend formed in the goods, and a measuring device on said carrier movable to position over the roll to engage the goods at a point coincident with said slot as the goods pass over said support.

6. In a device of the class described, a dispensing carrier constructed and arranged to removably support a roll of goods and permit the goods to be unrolled therefrom, measuring means mounted on said carrier and adapted to engage the goods when said carrier is in horizontal position, and means for pivotally supporting said carrier for movement from vertical to horizontal positions, adapted to permit said carrier when in horizontal position to receive the roll of goods.

7. In a device of the class described, a dispensing carrier constructed and arranged to removably support a roll of goods and permit the goods to be unrolled therefrom, measuring means on said carrier, means for pivotally supporting said carrier for movement from vertical to horizontal positions, adapted to permit said carrier when in horizontal position to receive the roll of goods, and means for latching said carrier.

8. In a device of the class described, a dispensing carrier constructed and arranged to removably support a roll of goods and permit the goods to be unrolled therefrom, measuring means on said carrier, means for pivotally supporting said carrier, constructed to permit it to move to operative and inoperative positions, adapted to permit said carrier when in operative position to receive a roll of goods, and means for latching said carrier in either of said positions.

9. In a device of the class described, a dispensing carrier comprising a skeleton frame having a plurality of bars adapted to form

a longitudinal roll receiving recess, dispensing means on said carrier, and means for pivotally supporting said carrier, constructed to permit it to move to operative and inoperative positions and adapted to permit said carrier when in operative position to receive a roll of goods.

10. In a device of the class described, a dispensing carrier comprising a skeleton frame consisting of a series of bars adapted to form a recess for removably supporting a roll of goods, constructed to permit the goods to be unrolled therefrom, and a measuring device pivoted to one of said supporting bars and adapted to engage the goods.

11. In a device of the class described, a dispensing carrier constructed to support a roll of goods and permit the goods to be unrolled therefrom, a winding roll receiving the goods from the roll, a support between said rolls positioned to form a pronounced bend in the goods as it passes thereover, and a measuring device engaging the goods at the bend as it passes over said support.

12. In a device of the class described, a dispensing carrier constructed to support a roll of goods and permit the goods to be unrolled therefrom, a winding roll receiving the goods while being drawn from the roll, and a support between said rolls positioned to form a pronounced bend in the goods as it passes thereover, said support having a cutting slot extending therealong at the bend formed in the goods.

13. In a device of the class described, a dispensing carrier constructed to support a roll of goods and permit the goods to be unrolled therefrom, a winding roll receiving the goods while being drawn from the roll, and a support between said rolls positioned to form a pronounced bend in the goods as it passes thereover, the goods engaging face of said support being rounded and having a cutting slot extending therealong and at the bend formed in the goods.

14. In a device of the class described, a dispensing carrier constructed to support a roll of goods and permit the goods to be unrolled therefrom, a winding roll receiving the goods from the roll, a support between said rolls positioned to form a pronounced bend in the goods as it passes thereover, the goods engaging face of said support being rounded and having a cutting slot extending therealong and at the bend formed in the goods, and a measuring device engaging the goods coincident with said slot.

In testimony whereof I affix my signature this 21st day of July, 1917.

JOHN L. MUELLER.
